TICKET PAD AND HOLDER

Eugene M. Macdonald, Shaker Heights, Ohio

Application November 5, 1948, Serial No. 58,459

3 Claims. (Cl. 206—40.6)

1

This invention relates to improvements in ticket or receipt pads and holders therefor, in which one portion of each receipt is held within the holder to form an auditor's stub while the other portion is exposed to be manually severed for the customer and the auditor's stub and customer's receipt correspondingly marked by adjustable cutters on the holder as the customer's receipt is severed from the pad.

It has been common practice to employ such generally described pads and holders for various usages, particularly for public transportation purposes. For instance, a passenger alights a motor bus for hire and pays the operator the required fare for travel from one station to another within the two terminals of the run of that bus. The operator adjusts one marker to align itself with a "Fare," or "Ticket," notation, another with a starting station notation and another with a destination notation appearing visibly on the customer's portion of the pad, severs the same and hands to the customer passenger. The passenger keeps his receipt until he arrives at his destination, at which time he returns it to the operator, but during his ride he has a paid receipt for transportation for the distance for which he has paid. Usually the marker cuts a notch in the customer's receipt while leaving a projection in the auditor's stub.

The conventional arrangement is such that for such usages as bus transportation slips considerable expense is entailed in the printing of the pads of slips themselves. In addition to the name of the company, instructions as to use and procedure and other collateral printing, there is the matter of printing in parallel duplicate, both on the customer's and auditor's side of each slip, a long list of stations on a given bus run. Additionally each pad, so printed, is useless except on its particular given run and on no other. Moreover, in the event of a rerouting or change by addition of a station in the bus run that pad and thousands of like pads printed in advance are rendered useless.

It is therefore one of the primary objects of my invention to provide an improved pad and holder therefor, which pad may contain the minimum amount of printed material and yet be capable of universal use.

A more particular object of my invention is to provide the pad with the most simple indicia, arranged parallel on the customer's and auditor's side of each slip, and provide a series of indestructible master cards to be interchangeably carried by the holder and each of such cards to

2

contain specific information, such as station designations for a given bus run, in addition to the simple corresponding symbols of the receipt pads, whereby the same pads may be used in conjunction with any number of master cards containing information as to each particular bus run.

A further object is to provide in such an improved arrangement a means whereby when the cutting markers are adjusted the other end of each will serve as a pointer on the visible master card.

With the foregoing and other objects in view, the invention resides in the combination of parts and in the details of construction hereinafter set forth in the following specification and appended claims, certain embodiments thereof being illustrated in the accompanying drawings, in which:

Figure 1 is a fragmentary plan view of the face 20 of one slip of a receipt pad in which the customer's receipt has been severed from the auditor's stub and showing the parallel symbols and markings left at their adjacent edges in the severing operation;

Figure 2 is a top plan view of the holder, showing a portion of the exposed customer's receipt portion of the top slip of the pad and also showing the master card visible through a window in the holder;

Figure 3 is a top plan view of the holder, partly 30 broken away, with the pad and master card removed, showing the marking cutters and indotted lines their internally arranged supporting rod and stub retaining flanges;

Figure 4 is a bottom plan view of the holder 35 in opened position;

Figure 5 is a view in cross section through the holder and pad in assembled position and ready for ticket severing operation; and

Figure 6 is a similar sectional view, showing the hinged holder bottom pushed inwardly to permit the stubs to be retained by the holder flanges after detachment of the customer's receipt from the stub.

Referring more particularly to the drawings, the ticket holder includes, as an integral entity, a front wall 1, a top wall 2, an inclined wall 3 and a rear wall 4, the bottom being open. The cover for the open bottom includes a plate 5 hinged at 6 to the bottom of the rear wall 4 and normally urged downwardly and open by an inner flap 7 also pivoted at 6 and spring pressed by springs 8. To plate 5 at 9 is hinged a forward bottom plate 10 normally urged upwardly by springs 11. Plate 5 is provided with two or more

longitudinally arranged inwardly projecting studs 12 to engage perforations 13 in the pad of tickets, generally indicated at 14 and later to be described in detail.

Further following the conventional practice, plate 5 is provided with an inner guideway 15 to receive a pair of flat locking rods 16, each provided near their inner adjacent ends with an operating button 17 that slides in a slot to be engageable manually below the bottom surface of plate 5. These two buttons are normally forced apart in their slots by a leaf spring 18. Thus, after flap 7 is raised a pad of tickets is inserted over studs 12 and the flap released to hold them in place. The two buttons 17 are pressed toward each other while inward pressure is applied on plate 5 until rods 16 are within the two bottom end flanges 19 to lock the bottom plates 5 and 10 in the position generally indicated in Figure 5. It is further general practice to position a series of longitudinally slidable cutters to be adjacent the bottom of the front wall so that as each customer's coupon is severed along the severing edge, defined by the lower end of the front wall, the marking cutter indents a notch in the edge of the customer's receipt while leaving a corresponding projection on the remaining auditor's stub. In such practice the identical vital information appears in parallel duplicate on the customer's receipt and the auditor's stub and, in the case of a bus ticket, this entails a repetition of printing of a long list of stations in duplicate.

As stated before, this practice is costly and wasteful. For instance, such a printed pad is useful for one particular bus run, only, and no other. Also in the event of a rerouting or any change in stations or station identification, the pad, and all like it, become useless.

Therefore, I contemplate the provision of a pad of tickets that may be universal in use and I have generally indicated the same in Figure 1. Instead of, for instance, printing the duplicate long lists of names of stations, I print a parallel duplicate of numbers, or other symbols, say from numbers 1 to 37 or any other series of numbers which would be estimated to be sufficient for the longest list of stations for any known or contemplated bus run.

This being a part of my invention it necessitates a revision of the conventional holder and such reorganization to make my new system of ticket pads feasible comprises the other part of my invention. Accordingly, I provide on the top wall 2 a superimposed longitudinal channel way 20 to receive a transparent window 21, underneath which I may removably slide a master card 22. As viewed in Figure 2, the top end of the channel way is closed and the bottom end open to permit insertion and withdrawal of the master card. At the lower end of the guideway 20, and in top plate 2, is a half-round button B, normally spring pressed upwardly to have its flat side engage the end of the master card. Pushing down on button B permits the master card to be removed and replaced. The master card is shown with such notations as "Half Fare," "Ticket" and "Full Fare" which three are identical with that of the customer's coupon 23, and as a matter of fact, with that of the auditor's stub 24 which is hidden in the holder. The master card further lists thirty-seven stations by name, opposite which are the numerals 1 to 37, inclusive. The master card may also have on its face a "Zone" number, here shown as zone 6.

Use of such a system involves a further modification of the conventional holder in that I prefer to have a pointer for the master card in conjunction with each coupon cutting marker.

Accordingly, I mount in the end walls an internal longitudinally extending rod 25, about which I loop a hard spring metal member, generally indicated as 26 in Figures 5 and 6, which is longitudinally slidable in suitable slots in front wall 1 and top wall 2. One end of member 26 terminates in a pointer 27 to slide along channel 20 over a portion of the window over the master card 22 and the other end terminates in a pointed cutting edge 28 to engage the pad at the holder severing edge 33. As shown in Figure 2, three, or more, of such combinations of pointers and markers are generally indicated at 26, 29 and 30.

For example, assume the bus run is from the station "Viking" to "Raven" and the passenger alights at "Bower" and pays full fare to "Midway," both intermediate stations. The operator moves member 26 until on the master card its pointer registers "Full Fare," member 29 until its pointer registers on the master card with 25 "Bower-10" and member 30 until its pointer registers on the master card with "Midway-30." He knows that the cutter ends must likewise register on the customer's coupon with "Full," "10" and "30." He severs the customer's receipt along the cutting edge and hands it to the customer, who at the end of the ride returns the same. During his ride his coupon is a receipt for the transportation for which he has paid. The operator then flexes the bottom plates 5 and 10 inwardly about their hinges 6 and 9 and the forward edge of the auditor's stub 24 is caught and retained behind lips 31 punched out of a plate 32 welded to front wall 1 to store them out of the way for succeeding severing operations.

The master cards, for universal use of my ticket pad system, may in scope be divided into zones for a nation-wide transportation system. Rerouting or change of any particular run need not change its zone number but only requires a reprinting of one master card. At the end of the run, the operator merely removes the auditor's stubs, folds them and marks the back of the pack with a zone number corresponding to the zone number on the master card and to avoid losing them he may merely tuck them behind the interior leaf spring 33 in the holder wall for safe-keeping.

It is to be understood that the use of the number symbols on the master card opposite the station identifications is optional and I may elect to either use them or not as the occasion demands.

It is also to be understood that while I have illustrated my invention as especially suitable in connection with transportation systems, it is no manner limited to such use.

I claim:

1. In a holder for a pad of tickets and stubs with duplicate lines of symbols on each, the combination of a casing having means for holding and concealing said stubs, said casing being open at one end and through which open end said tickets extend to be exposed to view, a cutting blade on said casing at its open end with which cutting blade the line of juncture of said tickets and stubs is aligned, cutting fingers mounted on said casing to be slidable longitudinally thereof parallel with said cutting blade to mark both the tickets and stubs when torn along said blade, 70 an elongated master card containing a series of 75

parallel lines of identifying printed matter, a holder on said casing for removably receiving and holding said master card to align said lines of printed matter thereon with the corresponding lines of symbols on said tickets and stubs, said cutting fingers having their upper ends terminating in indicating pointers longitudinally slidably movable, with said fingers, on said casing over said master card holder to register with the lines of identifying printed matter thereon.

2. In a holder for a pad of tickets and stubs with duplicate lines of symbols on each, the combination of a casing having means for holding and concealing said stubs, said casing being open at one end and through which open end said tickets extend to be exposed to view, a cutting blade on said casing at its open end with which cutting blade the line of juncture of said tickets and stubs is aligned, cutting fingers mounted on said casing to be slidable longitudinally thereof parallel with and having their lower ends terminating adjacent the upper surface of said cutting blade to mark both the tickets and stubs when torn along said blade, an elongated master card containing a series of parallel lines of identifying printed matter, a holder on said casing for removably receiving and holding said master card to align said lines of printed matter thereon with the corresponding lines of symbols on said tickets and stubs, said cutting fingers having their upper ends terminating in indicating pointers longitudinally slidably movable, with said fingers, on said casing over said master card holder to register with the lines of identifying printed matter thereon.

3. In a holder for a pad of tickets and stubs with duplicate lines of symbols on each, the combination of a casing having means for holding

and concealing said stubs, said casing being open at one end and through which open end said tickets extend to be exposed to view, a cutting blade on said casing at its open end with which cutting blade the line of juncture of said tickets and stubs is aligned, resilient means for urging said cutting blade into engagement with said tickets and stubs at their line of juncture, cutting fingers mounted on said casing to be slidable longitudinally thereof parallel with and having their lower ends terminating adjacent the upper surface of said cutting blade to mark both the tickets and stubs when torn along said blade, an elongated master card containing a series of parallel lines of identifying printed matter, a holder on said casing for removably receiving and holding said master card to align said lines of printed matter thereon with the corresponding lines of symbols on said tickets and stubs, said cutting fingers having their upper ends terminating in indicating pointers longitudinally slidably movable, with said fingers, on said casing over said master card holder to register with the lines of identifying printed matter thereon.
